UNITED STATES PATENT OFFICE.

HAROLD HERON HOSACK, OF FARNHAM, ENGLAND.

POURING OR TEEMING OF MOLTEN STEEL OR METAL INTO INGOT OR LIKE MOLDS.

Application filed March 22, 1923. Serial No. 626,915.

To all whom it may concern:

Be it known that I, HAROLD HERON HOSACK, a subject of the King of England, and residing at Farnham, in the county of Surrey, England, have invented improvements in or connected with the pouring or teeming of molten steel or metal into ingot or like molds, of which the following is a specification.

10 This invention has reference to pouring or teeming molten steel and other metals into molds, generally called ingot molds, and to that system of pouring or teeming where means are employed in connection 15 with the mold, and inside same, for the diminution or obviation of splashing of the metal when poured into the mold from above, and thereby to diminish as far as possible, the oxidation of the metal, and 20 other deteriorating effects produced upon or in it, due to such splashing, and it also relates to that system wherein a tube or mold are moved in relation to each other; and the present invention has primarily for 25 its object and effect to provide a method and means or mechanism by which the effects referred to, are accomplished simply and inexpensively, and one without mechanical parts which are capable of being 30 reached by the metal from the ladle, or within the mold.

In the mode of effecting the prevention of splashing, and means employed, hereinafter described, the improvements under 35 this invention are comprised.

The mold or molds is or are moved upwards over a tube through which the metal is poured from the ladle, forming a cylindrical shield (preferably of as big a diameter as convenient), which when the mold is up, will be surrounded by it, the lower end of this tube being then near the bottom of the mold; and in this position the nozzle of the ladle, which is not raised and lowered, is opened, and metal poured into the mold; and as the metal falls down to the bottom its splashing are prevented from reaching the sides of the mold, being intercepted by the tube. As the mold is 45 filled, it is lowered say by a hydraulic raising and lowering ram, or other equivalent raising and lowering means, so that the bottom edge of the tube is slightly under or only just above the molten liquid surface; 50 and then when the filling is complete, the mold or molds are lowered out of the way

of the tube, and then another mold or set of molds are brought under the ladle nozzles, when the operation is repeated.

In some cases, the bottom portion of the 60 tube, or both bottom and top, may be of fire brick or the like, the upper portion being say surrounded with a metal cylinder, in which the fire brick is held.

In some cases, as in the case of large 65 ingots being produced, the ingot mold may be supported directly on a ram head, or like elevating and lowering means, without a carriage or truck.

When a tundish is used with the tube, it 70 receives the metal from the ladle, and thereby breaks up the head, so that the metal is delivered down into the mold at a reduced and relatively small or smaller head.

75 In the accompanying drawings, Figure 1 is an elevation showing one arrangement of plan or apparatus under this invention; Figure 2 is a section showing a tundish distributing device used in the apparatus; and Figures 3 and 4 are section and side view 80 showing the shield tube of the apparatus.

Figure 5 shows a modified arrangement and manner of operating the apparatus.

In the drawings, 1 is the ladle, 2 are the 85 shield tubes, 3 is the tundish into which the ladle discharges, and by which liquid is distributed to the tubes 2. 4 are the ingots molds, and 5 is the hydraulic ram by which the ingot molds are lifted and lowered.

90 Referring to the arrangement shown in Figures 1 to 4, in this case the molds 4 are carried on a wheel truck or trolley 6, which in use is supported on a table 7 on the end of the piston 8 of the ram 5; and in operating, the molds, say a pair of molds 4, will be placed on each trolley 6, and run on the rails 9 (which may be assumed to be in the bottom of a casting pit) on to the table 7 in succession, the main ladle 1 being in this case stationary.

The metal from the main ladle is tapped into the funnel 10, on the top of the tundish 3, and it runs through a passage 11 of fire brick in the dish, and is discharged 105 through two orifices into the upper open ends of the shield tubes 2, which are suspended from the tundish casting by screws 12.

When the molds are brought into the correct position, held by any suitable known 110 way on the ram table 7, they are raised by the ram, so that when in their upper posi-

tion the bottom of the tubes 2 will be near the bottom of the molds; and then, as the pouring goes on, and the metal rises in the molds, the molds will be lowered by the 5 ram, so that the lower ends of the tubes may always dip in the liquid or molten steel or be near it, so that splashing cannot take place as the molds become filled, and metal cannot be sprayed on to the 10 surface of the molds.

When the molds are filled, and lowered below the ends of the tubes 2, the trolley 5 is moved off the ram table, and another one brought into position, and the 15 operation is repeated.

The tubes 2 are preferably constructed as shown in Figures 3 and 4, and are made in two parts, the upper part consisting of a metal tube lined with a fire resisting material, tubes or lining, and the lower part 2^x being a fire resisting material only, and provided with lugs 2^{xx} which pass into angle slots in the upper metal tube, and when turned round in bayonet joint manner, they 25 are supported by the metal, in which they may be sealed by filling in the gaps of the slots not occupied by the lugs 2^{xx}.

A telltale device is used in connection with the tubes 2, so that the position of 30 the surface of the metal in relation to the lower edge of the tube part 2^x, can be seen by the person in charge of the apparatus.

In the case shown this signal device consists of a head 13 on a rod 14 outside the 35 tube 2, supported freely or loosely in guide lugs 15 on the outside of the tube; whilst the lower end of the rod has a fire clay or brick body 16, which normally stands near the lower edge of the tube part 2^x as shown; and which, when dipping into the liquid, will float, and when floated will indicate by the upper head 13 that the body 16, and the lower edge or lip of the tube part 2^x, is touching or in the liquid. The 45 signal thus given will serve to enable the operator of the ram to lower it at the required rate, namely, the rate at which the tube part 2^x will just be dipping or sealed in the liquid in the mold during the teeming 50 operation.

In the modification shown in Figure 5, instead of the molds being run under the stationary ladle, the molds are stationary, and the ladle is moved, and the hydraulic 55 ram 5 by which the molds are raised, is carried on the carriage 18 on which the main ladle 1 is supported.

In this case, as each set of molds is filled, the lifting chains 19, which are operated by the ram 5, are disconnected from the lifting trunnions or connecting parts 20 of the molds 4; and then the ladle carriage 18, and parts carried by it, are moved

over the next set or pair of molds, which are then lifted over the shield tube 2, similarly as in the arrangement above described. 65

It may be assumed that the tubes 2 in this case also, are substantially of the same construction as that set forth with reference to Figures 1 to 4, and are provided with telltale signal devices as in that case. 70

It will be understood that instead of the lifting and lowering operations being effected by hydraulic means, the operation 75 may be effected by hand or power winch, or in any suitable way.

What is claimed is:—

1. Means for pouring or teeming molten metal into ingot or like molds, comprising a stationary ladle, a stationary shield tube through which the metal from the ladle is adapted to fall, a mold adapted to be raised over the tube and subsequently to be lowered in pouring; said shield tube having a detachable lower end. 80

2. Means for pouring or teeming molten metal into ingot or like molds, comprising a stationary ladle, a stationary shield tube through which the metal from the ladle is adapted to fall, a mold adapted to be raised over the tube and subsequently to be lowered in pouring, and means for automatically indicating the relative positions 90 of the bottom of the shield tube and the level of the metal in the mold as the metal is delivered to the mold. 95

3. Means for pouring or teeming molten metal into ingot or like molds, comprising a stationary ladle and a stationary shield tube adapted to receive metal discharged or delivered from the ladle, and comprising a metal outer part, a lining of fire resisting material, and a detachable lower part of fire resisting material having a part 100 adapted to engage with the lower edge of the aforesaid part; substantially as set forth. 105

4. Means for pouring or teeming molten metal into ingot or like molds, comprising a stationary ladle and a stationary shield tube adapted to receive metal discharged or delivered from the ladle, and comprising a metal outer part, a lining of fire resisting material, a signal rod device supported 110 on the outside of the said tube, and having a fire brick body on the lower end adapted to float in the metal; substantially as set forth. 115

In testimony whereof I have signed my 120 name to this specification in the presence of two subscribing witnesses.

HAROLD HERON HOSACK.
